Primary Examiner — J. Thorn, Sr.

(57) **CLAIM**

The ornamental design for a wetsuit as shown and described.

DESCRIPTION

1. Wetsuit

FIG. 1 is a front view of a wetsuit showing my new design;

FIG. 2 is a back view thereof;

FIG. 3 is a right-side view thereof; and,

FIG. 4 is a left side view.

The broken lines shown in the drawings depict an individual user wearing the wetsuit and are for illustrative purposes only that form no part of the claimed design.
